UNITED STATES PATENT OFFICE.

JOHN H. RIDDLE, OF AKRON, OHIO, ASSIGNOR TO CONRAD G. AUBLE, OF SAME PLACE.

SHAFT-COUPING.

SPECIFICATION forming part of Letters Patent No. 252,700, dated January 24, 1882.

Application filed November 28, 1881. (No model.)

To all whom it may concern:

Be it known that I, JOHN H. RIDDLE, of Akron, in the county of Summit and State of Ohio, have invented a new and useful Improvement in Shaft-Couplings, of which the following is a specification.

The object of my invention is to produce a shaft-coupling which shall be simple in construction, easily applied and removed, and which shall rigidly resist a longitudinal as well as a twisting strain. I attain these objects by devices illustrated in the accompanying drawings, in which—

Figure 1 represents the several parts of a coupling separated, the parts at the left of the center of the sheet being shown in section and those at the right in elevation; Fig. 2, a central cross-section of the sleeve B and key C; and Fig. 3, the coupling closed, uniting the two shafts.

Similar letters refer to similar parts throughout the several views.

The ends of the shafts A A' being turned to the same size, a key-seat, c, is cut in each, near the end thereof. These key-seats may be milled circular, in the form shown, or may be wedge-shaped and straight on the bottom, the essential feature being that their least depth shall be at or near the end of the shaft. Upon the ends of the shafts thus prepared slides a sleeve, B. This sleeve is constructed in one piece, and bored to accurately fit the shafts, and pierced in its thicker portion with a keyway, b. The

key C is adapted to fit the key-seats in the shafts and the keyway in the sleeve B. 35

Surrounding the sleeve B is a case, D D', made in two pieces, and adapted by a screw-thread, as shown in Fig. 1, or bolts, as shown in Fig. 3, to be connected and inclose the sleeve B and key C and hold the latter in place. No 40 especial form of construction is required for the case D D', it being essential only that it should surround the sleeve B, so as to hold the key C in place.

By this device either shaft may be removed 45 without disturbing the sleeve B by simply removing the case D D' and withdrawing the key C.

Having thus described my invention, I claim— 50

A shaft-coupling consisting essentially of wedge-shaped key-seats at or near the ends of the shafts, the least depth being near said ends, a sleeve constructed in one piece to receive said shaft ends, and provided with a keyway, 55 an independent key adapted to enter said keyway and fit the key-seats, and a case surrounding said sleeve and key, the whole constructed and arranged substantially as shown.

In testimony that I claim the foregoing I have hereinunto set my hand this 18th day of November, A. D. 1881.

JOHN H. RIDDLE.
